WEATHER STRIP

Samuel M. Funk, Indianapolis, Ind.

Application March 2, 1935, Serial No. 8,980

3 Claims. (Cl. 20—67)

The present application relates to a weather strip construction, and primarily to a sealing means for sealing the space between the lower edge of a swinging door and the cooperating threshold.

The primary object of the invention is to provide mechanism, absolutely automatic in its operation, which will provide a seal between the lower edge of the swinging door and the cooperating threshold, upon closing the door. Further objects of the invention will appear as the description proceeds.

To the accomplishment of the above and related objects, my invention may be embodied in the forms illustrated in the accompanying drawing, attention being called to the fact, however, that the drawing is illustrative only, and that change may be made in the specific constructions illustrated and described, so long as the scope of the appended claims is not violated.

Fig. 1 is a fragmental perspective view of the lower portion of a door;

Fig. 2 is an end elevation of a door and threshold, as viewed from the right of Fig. 1;

Fig. 3 is a sectional view taken substantially on the line 3—3 of Fig. 3 and looking in the direction of the arrows;

Fig. 4 is a transverse section taken in a plane perpendicular to the plane of Fig. 3; and

Fig. 5 is a view similar to Fig. 4, but showing a modified form of the invention.

Referring more particularly to Figs. 1 to 4 inclusive, it will be seen that I have illustrated a door 10 surrounded by the usual frame elements comprising a floor 11, an upright 12 adjacent the free edge of the door, and an upright 13 adjacent the hinged edge of the door. I have illustrated the door as provided with the usual weather-excluding threshold 14, normally provided with outside doors; but it is to be understood that such a threshold member 14 is not an essential of my invention, and that a floor which closely underlies the lower edge of the door may be, in all particulars, the equivalent of such a threshold member.

The door 10 is hinged as at 15 to swing outwardly, as viewed in Fig. 1.

Along its lower edge, the door 10 is formed with an elongated recess 16, the longitudinal extent of which is substantially equal to the lateral width of the door 10. At each lateral edge of the door there is provided a bracket member 17, set flush with the edge of the door, and provided with a boss 18 facing inwardly, each boss 18 being formed with a cylindrical socket 19.

In the sockets 19 are journaled the trunnions 20, one being formed at each end of a strip 21 which is preferably made of cast metal.

The trunnions 20 are formed in line with one longitudinal edge of the strip 21, whereby the opposite edge 22 of said strip is free to swing as the strip oscillates about the axes of the trunnions 20.

At the free edge 22, the strip is formed with a beveled surface 23 which leads to a groove 24 in which is received a strip of rubber, or other compressible material 25. The portion 26 of the strip 21 is cut back, as is clearly shown in Figs. 2 and 4.

That edge of the strip 21 on which the trunnions 20 are formed is preferably formed as a radiused surface 27 centered on the axes of the trunnions, for a reason later to be brought out.

The strip 21 is formed, on its upper surface, with a lug 28 perforated for the reception of one end of a spring 29, the opposite end of which is anchored on a screw 30 seated in the upper wall of a suitably formed recess 36. The lug 28 is preferably formed substantially midway between the ends of the strip 21, or, as an alternative, the strip may be provided with two or more lugs 28, suitably spaced along its length, and each cooperating with a spring similar to the spring 29. As will be obvious, the spring 29 tends to hold the strip 21 in the position illustrated in Fig. 4.

The upper wall of the recess 16 is formed with a groove 31 in which is received a strip 32 of rubber, or other suitable compressible material. Said strip 32 has a sealing engagement with the radiused surface 27 of the strip 21 whereby, as said strip 21 oscillates about the axes of the trunnions 20, a sealing engagement is constantly maintained without varying the degree of compression of the strip 32. Of course, the purpose of the strip 32 is to seal the space between the weather strip 21 and the upper wall of the recess 16 against air flow through said recess from one side of the door to the other.

At a suitable point in its length, preferably adjacent one end thereof, the strip 21 is provided with a downwardly projecting lug 33 which, even in the position illustrated in Fig. 4, projects slightly from the recess 16. When the door 10 is moved to closed position, the lug 33 engages an abutment member 34 carried upon a plate 35 set flush in the threshold 14, said abutment member 34 projecting, of course, above the surface of the threshold 14 and into the path of the lug 33.

It will be entirely clear that, as the door 10 is

5 moved toward open position from the position shown in Fig. 2, the spring 29 will tend to rotate the strip 21 in a counterclockwise direction about the axes of the lugs 20, such rotation being resisted only by the engagement of the lug 33 against the abutment member 34. As the door begins to move in an opening direction, the strip 21 will be so rotated until, as the lug 33 leaves the abutment member 34, the strip 21 will have assumed the position illustrated in Fig. 4. Now, when the door is again moved toward closed position, the projecting portion of the lug 33 will engage the abutment member 34 just before complete closure is effected; and as the door 10 10 is brought to its final position, the edge 22 of the strip 21 will be thrown down into the position illustrated in Fig. 2. As the strip 21 is so swung, of course the leading corner of the compressible strip 25 will first engage the threshold; 15 and completion of the door-closing movement will compress and deform that corner of the strip 25 so that a true sealing engagement between the strip 25 and the threshold 14 will be effected.

20 The embodiment of Fig. 5 is quite similar. A door 37 is formed with a recess 38 similar to the recess 16, and a metal strip 39 is suitably mounted in said recess. The free edge of the strip 39 is formed with a socket 40 for the reception of a strip 41 of rubber, or other compressible material. Said strip 39 is also provided with a lug 42 in which is engaged one end of a spring 43 suitably anchored in the door and tending to lift the free edge of the strip 39 into the socket 38.

25 35 A socket 44 formed in the door receives a strip 45 of very highly compressible material which engages constantly against the upper surface of the strip 38, said material 45 being deformable, as the strip 39 is moved into the recess 38 under 40 the effect of the spring 43.

A lug 46 on the strip 39 cooperates with a lug 47 set into the threshold, the cooperative effect

of said two lugs being identical with the effect of the lugs 33 and 34.

I claim as my invention:

1. In combination with a swinging closure, means for sealing the space between an edge of said closure and its frame comprising an element hingedly mounted within said closure, means automatically operable, when said closure is moved to closed position, to rotate said element into intimate contact with said frame, and a strip of soft rubber or the like sealed in said closure and engaging a portion of said element concentric with the hinge-axis thereof substantially throughout the length of said element. 5

2. The combination with a closure having a recess formed in its lower edge and having a longitudinal extent substantially equal to the width of the closure, of a weather strip oscillably mounted in said recess and comprising a radiused surface centered on the axis of oscillation of said strip, spring means resiliently holding said strip substantially entirely within said recess, means operable upon movement of said closure to swing said weather strip out of said recess and into intimate contact with the frame of said closure, 20 and a strip of compressible material sealed in said closure within said recess and having a sealing engagement with said radiused surface. 25

3. The combination with a closure having a recess formed in its lower edge and having a longitudinal extent substantially equal to the width of the closure, of a weather strip oscillably mounted in said recess, spring means resiliently holding said strip substantially entirely within said recess, means operable upon movement of said closure to swing said weather strip out of said recess and into intimate contact with the frame of said closure, and a strip of compressible material sealed in said closure within said recess and constantly maintaining a sealing engagement 40 with an upper surface of said weather strip. 35

SAMUEL M. FUNK.
